DESIGN FOR A TOILET SEAT

James D. Williams, Jr., Leavenworth, Ind.

Application January 10, 1945, Serial No. 117,369

Term of patent 14 years

(Cl. D4—5)

To all whom it may concern:

Be it known that I, James D. Williams, Jr., a citizen of the United States, residing at Leavenworth, in the county of Crawford and State of Indiana, have invented a new, original, and ornamental Design for a Toilet Seat, of which the following is a specification, reference being had to the accompanying drawing, forming part thereof.

Figure 1 is a plan view of the toilet seat showing my new design.

Figure 2 is a rear elevation of the toilet seat.

Figures 3 and 4 are opposed side elevations of the toilet seat.

Figure 5 is a front elevation of the toilet seat.

Figures 6, 7 and 8 are cross sectional views taken thru the toilet seat substantially on the respective lines shown in Figure 1 of the drawing.

I claim:

The ornamental design for a toilet seat, as shown.

JAMES D. WILLIAMS, JR.
